DEVICE FOR RESISTING MOVEMENT OF THE ARM OF DRILLS

Filed Sept. 29, 1941

UNITED STATES PATENT OFFICE

2,366,110

DEVICE FOR RESISTING MOVEMENT OF THE
ARM OF A DRILLWilliam G. Hoelscher, Cincinnati, Ohio, assignor
to The American Tool Works Company, Cincinnati,
Ohio, a corporation of Ohio

Application September 29, 1941, Serial No. 412,768

1 Claim. (Cl. 77—27)

This invention relates to machine tools and is particularly directed to improvements in radial drills. More particularly, the invention is concerned with improvements relating to the control of the arm movement.

In certain types of work, such as for example, where a number of holes are to be drilled in a piece of work, considerable time is lost in clamping and unclamping the arm. In all radial drill structures heretofore known, the arm is arranged to swing freely; that is, it may either swing on the column or it may swing as a unit with the column on a stump. A clamping device is provided for fixing the arm in a selected position so that the spindle is in registry with the hole to be drilled, whereby the arm cannot swing during the drilling operation. Where smaller holes are to be drilled and the drilling thrust is not great, it has been the practice to perform the drilling operations without clamping the arm, but this is not efficient, for disaligned or otherwise inaccurate drilling is apt to result.

Accordingly, it has been the object of the present inventor to provide an improved structure wherein a predetermined amount of resistance may be applied to the arm for holding it in position against displacement unless a certain amount of pressure is applied to the arm. In other words, the purpose here has been to provide a resistance means in connection with the arm for holding the arm relatively fixed, but not immovable, in the drilling position.

As a result of this improvement, it is possible for the operator to dispense with the use of the normal clamping means; that is, the one which fixes the arm against any movement, and utilize the resistance means in cases where drilling operations are small and where there are several operations on one piece of work. Thus, the operator, having set the resistance means, may drill the hole without concern about displacement, and when the drilling operation has been completed, he may, by the exertion of manual pressure on the arm move the arm into position for drilling the next hole without the necessity of releasing a clamp.

A structure resulting from this concept may consist of a lever-operated tightening means effective upon the column for tightening it around the stump, thereby creating a frictional fit between them. In those cases where the arm rotates directly on the column, the same tightening principle may be employed for tightening the arm directly upon the column.

Other objects and certain advantages of the invention will be more fully apparent from a description of the drawing in which:

Figure 1 is a perspective view of a radial drill incorporating the present invention.

Figure 2 is a fragmentary side view of a portion of the drill showing the lever for the device of the present invention for applying a resistance to column movement relative to the stump.

Figure 3 is a fragmentary side view partially in section, taken at right angles to Figure 2 for illustrating the relationship of the resistance applying means and the normal clamping means.

Figure 4 is a sectional view taken on line 4—4, Figure 3, detailing the resistance applying means.

Figure 5 is a sectional view taken on line 5—5, Figure 3, illustrating the limit stop means for the normal clamping device.

For the purpose of illustrating the invention, an otherwise conventional radial drill has been depicted. The radial drill disclosed is of the type in which the arm and column rotate as a unit and accordingly, the resistance device is placed on the column for action thereon to set up a predetermined drag or resistance on the stump. In general, the device is arranged so as to provide an easily accessible handle operating a tightening means incorporating an adjustable stop so that the amount of drag or resistance may be predetermined.

Referring to the drawing, the base of the radial drill is indicated at 10 and includes a stump member indicated at 11. The column is indicated at 12, the arm at 13, and the head at 14. It is not considered necessary to describe in any way the details of the drill other than the structure at the base of the column, at which point the device of the present invention is illustrated.

The column includes the usual enlarged base portion 15 fitted over the counter-turned portion 16 of the stump. A thrust bearing 17 is disposed on the shoulder 18 of the stump and bears the weight of the column by engagement within the internal shoulder 19 of the column. This enlarged portion of the column is inclusive of a split section providing slightly spaced radially extended portions 20 separated by the split and further rendered flexible by means of a circumferential slot 21 in the portion 15 of the column just above the radially extended portions and intersected by the vertical split.

Generally described, the normal clamping means consists of an arm 22 having a pivotal

abutment with one section 20 through an element 23 and swung on this abutment by means of a cam 24 fixed on a shaft 25 mounted on the column base. A draw bolt 26 traverses the radially extended split portions and the pivoted end of the arm. This draw bolt includes abutment elements at each end. The effect of outward swinging movement of the arm 22 is to pull the portions 20 together to clamp the base of the column on the stump. A lever 27 rotates the shaft 25 through another shaft 28, and bevel gears 29-29. As shown in Figure 5, the clamping movement of the shaft 25 is limited by means of a stud 30 adapted to engage limit stops 31-31 fixed to the base of the column.

The resistance device of this invention, in the preferred embodiment, is located adjacent the main clamping lever 27. In the present disclosure, it is located just beneath the shaft 28 and consists of a rotatably mounted shaft 34 journaled in an outer casing wall 35 of the column and in one clamping portion 20. The shaft 34 extends across the split and has a screw threaded portion projecting into a screw threaded bore 36 of the other split portion 20. The shaft 34 includes a shoulder 37 lying against a shoulder within the bore of the split portion 20, whereby rotation of the shaft in one direction will, through the screw threads, tighten the split portions upon the stump and in the other direction will loosen them.

An operating lever or arm 38 is fixed to the outer end of the shaft 34 and depends therefrom (Figure 2). This lever includes a manipulating knob 39 at its lower end. It is limited in its swinging movement by means of a fixed stop 40 and an adjustable stop 41. The fixed stop consists of a screw engaged into the outer surface of the casing wall 35. The adjustable stop consists of a plate 42 having a slot 43 therein traversed by a fastening screw 44 engaged through the slot into the casing wall 35. The slot extends at right angles to the end of the plate to be

abutted by the lever and thus, the position of the abutted end may be varied to permit more or less swing of the lever. Accordingly, it is possible to place a predetermined amount of resistance or drag on the movement of the column and arm on the stump.

In those cases where the drilling operations do not require a fixed or immovable position of the arm, the operator merely swings the lever 38 to the left. This tends to clamp the column against accidental or easy movement and makes it necessary to apply a certain amount of pressure against the arm before it can be moved to another drilling position. By using the adjustable plate, the operator can set the resistance to the exact amount required for efficient operation.

The adjustable stop plate 42 is mounted so that it has a fair range of adjustment but in no event can it be moved far enough away from the fixed stop 40 to permit movement of the resistance applying lever sufficient to lock the column in position. As a matter of fact, the resistance applying means is not constructed for applying a clamping or locking pressure. Its operation is supplemental to the operation of the normal clamping lever.

Having described my invention, I claim:

In a radial drill, a base presenting a stationary member; an arm, means for mounting said arm relative to said base, means for clamping said arm against relative movement including a contractible member for engaging said stationary member, means including a lever for causing a partial contraction of said contractible member whereby a yieldable resistance to rotative movement of said arm is provided, and positive adjustable stop means operable in conjunction with said lever for limiting the degree of said partial contraction whereby manipulation of said lever to said stop means provides a predetermined drag against rotative movement for said arm.

WILLIAM G. HOELSCHER.
